TOY CONSTRUCTION KIT

May J. Robins, Katonah, N. Y.

Application October 9, 1935, Serial No. 44,153

10 Claims. (Cl. 46—26)

My present invention relates generally to toys, and has particular reference to an improved type of construction kit.

The present toy is of the building block variety, the elements being composed preferably of wood or equivalent material. One of the main objects of the invention is to provide a novel combination of elements, cooperable in a unique manner, to permit the assembly of selected elements into a variety of toy structures.

The invention is primarily directed toward the very young child, and aims to provide a toy of high educational value, the elements and their mode of assembly being characterized by unusual simplicity, yet embodying novel features which confront the child with problems of varying difficulty, requiring and enabling him to employ a certain amount of ingenuity in assembling the elements in different ways.

20 The interconnection and mutual assembly of the elements is grounded upon the fundamentally simple interengagement of a rod-like element or pin with a hole or recess. The kit makes provision for two different basic cross-sections of pins, every step of interconnection or assembly involving, in one form or another, the engagement of a pin element of particular cross-section with an opening or bore of corresponding cross-section. Accordingly, one of the first things 30 which the child learns, in using the present kit, is that a large pin will not go into a small hole; or, stated more generally, that a pin of particular cross-section fits snugly and accurately only into a bore of corresponding cross-section.

35 Briefly, the present toy comprises a variety of different elements which may be conveniently classified as main structure elements, pins, and connectors. The main structure elements consist primarily of slab-like members having a variety of different bores therein, including marginal keyhole bores. The pins are provided in two sets, one set having cross-section #1, the other set having a different cross-section #2. Preferably, one of the cross-sections is smaller in 45 area than the other. The connectors are unique bodies, prismatic in nature, and of dumb-bell shape, thereby enabling them to be engaged with-in the keyhole bores hereinbefore mentioned.

In accordance with the fundamental concept 50 of the present invention, the connector heads and the bores all conform to the basic cross-sections defined by the two sets of pins.

Various other auxiliary elements enter into the present kit, and will be described in greater detail hereinafter.

I achieve the foregoing objects, and such other objects as may hereinafter appear or be pointed out, in the manner illustratively exemplified in the accompanying drawings, wherein—

Figures 1 through 1e are perspective views, respectively, of various slab members embodying the features of the present invention;

Figures 2 through 2b are perspective views, respectively, of auxiliary blocks;

Figures 3 through 3b are perspective views, respectively, of different female-type connectors;

Figures 4 through 4e are perspective views, respectively, of different types of dumb-bell-type connectors;

Figures 5 and 5a are perspective views, respectively, of the type of pins entering into the kit;

Figure 6 is a perspective view of a wheel element;

Figure 6a is a perspective view of a retaining pin;

Figure 7 is a perspective view of a simple assembled structure;

Figure 8 is a cross-sectional view taken substantially along the line 8—8 of Figure 7;

Figure 9 is a perspective view of another possible structure;

Figure 10 is a perspective view of an extremely simple toy structure;

Figure 11 is an exploded view showing another illustrative assembly of elements;

Figure 12 is an exploded view showing a further illustrative assembly of elements; and

Figure 13 is a perspective view of a group of slabs showing their possible utility as form boards.

In Figure 1 I have illustrated a slab 10 which is substantially rectangular and which is provided at its opposite ends 11 with the marginal keyhole bores 12 and 13. By the term "keyhole bore" I refer to an opening or recess having an enlarged inner portion and a narrowed shank portion arranged perpendicular to the edge.

In addition to the marginal bores 12 and 13, the slab 10 is provided with the medial bores 14, 15, and 16. The bores 14 and 15 extend transversely through the block, while the bore 16 extends downwardly into the upper face but does not necessarily continue all the way through the block.

While the elements may obviously be of varying sizes, it is preferable to make the width of each rectangular slab bear a simple proportion to the length. Thus, the slab illustratively shown in Figure 1 has a width exactly half of the length. The bore 16 is preferably arranged at the mid-

point, and the bores 14 and 15 are preferably arranged midway between the center of the slab and the ends thereof.

For purposes of illustration, I have shown the bores 12 and 13 of relatively large diameter, corresponding to the diameter of the pin 17 shown in Figure 5a. This pin forms one of a set of similar pins of varying lengths, yet all of uniform cross-section. I have shown also the bores 14, 15, and 16 of relatively smaller cross-section or diameter, this cross-section conforming to that of the pin 18 shown in Figure 5. This pin forms one of the second set of pins, also of varying lengths, yet all of uniform cross-section.

15 For illustrative purposes, I have shown the pins 17 and 18 of circular cross-section, and the bores shown in the other drawings are, therefore, of corresponding circular configuration and area. It will be understood, however, that the main 20 features of the invention do not require circular cross-sections to be employed. The pins of one set, e. g., of the type shown in Figure 5a, might be of square, triangular, or other particular cross-sectional configuration; whereas the pins of the 25 other set might also have cross-sectional configurations other than circular. It is not even essential, from all aspects, that one set of pins be smaller in cross-section than the other; nor that the configuration of one set be the same as 30 that of the other. In its simplest form, however, and hence in a preferred embodiment of the invention, the basic concept has recourse to the fundamental circular cross-section, and it is for this reason that the pins and bores and other 35 corresponding elements have been illustrated herein of circular cross-section.

The slab 16 of Figure 1 is merely typical of similar slabs that may have different lengths and widths. All of the slab elements, however, are 40 preferably of the same thickness.

In Figure 1a I have shown a slab 16 which has the shape of a right-angle 45° triangle. On the edge 26, constituting the hypotenuse, I provide a marginal keyhole bore 21 which I have shown 45 identical with the bores 12 and 13 of Figure 1.

In Figure 1b, the slab 22 is identical with the slab 16 with the exception that the marginal keyhole bore 23 is of a smaller size, whereby the inner or main portion conforms to the basic cross-section of the pin 18 of Figure 5. Preferably, the distance between the center of the bore and the edge 24 is the same as the corresponding distance in Figure 1a. In general, it may be stated that where bores of one or the other diameter or cross-section are alternatively provided, the distances between centers are maintained constant.

In Figure 1c, the slab 26 is in every respect similar to that of Figure 1a, except that the slab is semi-circular in configuration, instead of triangular. The marginal keyhole bore 26 is identical with the bore 21 and conforms to the basic cross-section of the pin 17 of Figure 5a.

In Figure 1d a slab 27 is shown, identical in every respect with the slab of Figure 1, except that the medial bore 28 is of the larger size, as compared with the bore 16 of Figure 1. The bore 28 may or may not extend all the way through the slab, and it preferably does not extend all the way through; and it conforms to the basic cross-section of Figure 5a.

In Figure 1e, I have shown a slab 29 having the same width as the slabs 16 and 27, but having a length twice as great as either of the latter. The slab 29 has a marginal keyhole bore 30

adjacent to the edge 31, a similar bore 32 adjacent to the edge 33, and a bore 34 adjacent to the edge 35. The bores 30 and 34 are of the cross-section conforming to Figure 5a, while the bore 32 is of the other basic cross-section conforming to the pin 18 of Figure 5. The slab 29 is merely illustrative of the large variety of different slabs that may be constructed, and it will be understood that the possible variations in arrangement of bores is very great. Essentially, 10 and fundamentally, however, all of the bores in the slabs conform to the basic cross-sections of the two sets of pins 17 and 18.

It is within the purview of my invention to embellish the slabs and other elements, and, 15 under certain circumstances, to provide relatively large recesses 103 in the upper faces of the slabs, as shown in Figure 13. This renders the slabs useful as "form boards", i. e., the recesses 103 would be triangular, square, circular, etc., 20 for the purpose of enabling a child to insert blocks 104 of corresponding cross-section into the recesses.

In Figure 2, I have illustrated an auxiliary block 36 which is preferably, though not necessarily, of square cross-section, and is thus different from the slabs of Figures 1-1e. I have shown the block 36 with a medial transverse bore 37 of the larger variety.

The auxiliary block 38 of Figure 2a is identical 30 with the block 36, except that the medial bore 39 is of the smaller variety.

The auxiliary block 40 of Figure 2b is circular in cross-section, and the medial transverse bore 41 is of the larger variety.

Obviously, many other auxiliary blocks of this character may be provided, the configurations and lengths of Figures 2-2b being merely illustrative. Other bores may also be provided, in a large variety of different relationships, but, essentially, all of the bores conform to the basic cross-sections of the two sets of pins.

In Figure 3, I have illustrated a female-type connector whose utility will be hereinafter described. It consists of a flat body 42 having 45 spaced bores 43. These bores have been shown of the larger variety.

The connector 44 of Figure 3 is similar, except that only two bores 45 are provided. The connector 46 of Figure 3b is in every respect similar to 50 that of Figure 3a, the bores 47 being the same as the bores 45, but the exterior contour of the connector is somewhat different.

The bores of Figures 3-3b may be of the larger or the smaller variety, or, more accurately, of the type #1 or type #2 cross-section, depending upon the basic cross-sections which the pins 17 and 18 are caused to embody.

In Figures 4-4e, I have illustrated various modified forms of the main type of connector. In 60 Figure 4, I have shown a prismatic body 48 of dumb-bell shape, whereby the opposite heads 49 and 50 are provided, interconnected by the integral medial web portion 51. The body 48 is preferably of the same thickness as the slabs of Figures 1-1e; and the connector heads 49 and 50 conform to the basic cross-sections hereinbefore mentioned. In the particular connector illustrated in Figure 4, the two heads 49 and 50 are each of a cross-section conforming to 70 that of the pin 17.

In Figure 4a, the connector 52 has opposite heads 53 and 54 which conform to the basic cross-section of the pin 18. As hereinbefore mentioned, the distance between the centers of the heads 75

53 and 54 is the same as the distance between the centers of the heads 49 and 50.

In Figure 4b, I have illustrated a connector 55 in which one head 56 conforms to one basic cross-section, while the opposite head 57 conforms to the other basic cross-section.

In Figure 4c, the connector 58 is in every respect the same as that of Figure 4, except that the head 59 has been shown provided with an axial bore 60, this bore conforming to the basic-cross-section of the pin 18.

Obviously, other variations will readily suggest themselves. Both heads might, for example, have axial bores therein; or the larger head of Figure 4b might have an axial bore. Similarly, where the basic cross-section of the pins 18 is other than circular, the bore 60 would conform in cross-section.

In Figure 4d, I have shown a modification which is desirable in assembling certain structures. The connector 61 is identical with that of Figure 4, except that a marginally projecting shoulder element 62 is fastened or mounted to one end of the connector head 63, while a similar marginally projecting shoulder 64 is arranged on the opposite end of the connector head 65. The use of this connector will be explained hereinafter.

In Figure 4e, a further modification has been shown in which the connector 66 has the opposite heads 67 and 68, and is also provided with the additional pin-like projection 69 mounted on the midportion of the body, with the axis of the projection 69 parallel to the axes of the heads 67 and 68. Needless to say, the projection 69 conforms in cross-section to one of the basic cross-sections. I have illustratively shown it conforming to the cross-section of the pin 11.

The pins 17 and 18 have already been alluded to, and in passing I draw attention to the fact that the smaller pin 18 will preferably have the transverse bores 70 near its ends, for the purpose of receiving retaining pins 71 (Figure 6a) designed to hold a wheel 72 (Figure 6) on the pin 17. The wheel 72 is in the form of a disc having a central opening 73 which, obviously, conforms to the cross-section of the pin 18.

There are innumerable ways in which the elements of the present kit may be interconnected and assembled, and it will, therefore, be understood that the toy structures illustrated in Figures 7-12, and now to be described, are purely illustrative of the capabilities and characteristics of the present invention.

Fundamentally, every assembly involves the engagement of some pin-like element with a corresponding opening or bore. This may be accompanied by a stacking of the slabs or blocks, one above the other, or by arranging them in juxtaposition; or it may partake of the extremely simple assembly shown for illustrative purposes in Figure 10. In this figure, a slab 74, similar to the slabs 18 and 29 yet of an intermediate length, is assembled with a pin 75 selected from the set to which the pin 17 belongs. To a very young child, the toy structure thus produced might well constitute a steam locomotive. This structure illustrates the cooperability between the pins and the keyhole bores, notwithstanding the fact that these bores are also adapted for engagement by connectors of the type illustrated in Figures 4-4e.

In Figure 7, for example, a slab 76, corresponding in every respect to the slab 18 of

Figure 1, is assembled with an auxiliary block 77 similar to the block shown in Figure 2b except that the medial bore is of the smaller variety. A pin 78, selected from the set to which the pin 18 belongs, passes through the bore in 5 the block 77 and thence into the medial bore in the upper face of the slab 76. This produces a structure bearing a certain resemblance to a tank car. For the purpose of enabling this structure to be inter-connected with other similar structures, a connector 79 may be engaged with one of the keyhole bores. This would permit another "car" to be arranged in endwise relation to the slab 76, the two being thereupon interconnected by the connector 79.

The transverse bores 80 of the structure of Figure 7 fulfill no purpose, but in Figure 9 a structure is shown in which these bores accommodate pins 81, such pins serving as axles upon which the wheels 82 may be mounted. To hold 20 the wheels in place, the retaining pins 83 (like that of Figure 6a) are employed. In this structure, a slab 84 is used similar to the slabs 18 and 76, and a pin 85 constitutes an adornment for the "car".

The structure of Figure 9 illustrates the utility of the connector of Figure 4d. The projecting shoulder 62 keeps the connector from slipping through the keyhole bore, which it would otherwise do because of the fact that the slab 30 84 is raised from the floor. Similarly, the projecting shoulder 64 serves as a rest for the adjacent slab that may be engaged over the connector head 65. The shoulder 64 is not absolutely essential.

In Figure 11, I have illustrated an assembly of elements consisting of two elongated slabs 86 and 87. They are arranged in side-by-side relation, and a triangular slab 88, similar to but larger than the slab of Figure 1a, is arranged 40 at the end. An ordinary connector would be of no avail in this assembly because the keyhole bores 89, 90, and 91 are not in aligned juxtaposition. However, the parts may be interconnected by selecting pins 92 from the proper set, 45 and then applying the female-type connector 93. The latter will ultimately rest upon the upper surface of the slabs 86, 87, and 88, and will interconnect the pins 92.

Furthermore, the pins 94, selected from the proper set, may be inserted transversely through 50 the bores 95 provided in the slabs 86 and 87, thereby helping to hold these slabs in juxtaposed relation.

In Figure 12, I have shown an arrangement of 55 slabs 86, 87, and 88 wherein the keyhole bores 99 and 100 are in alignment, but wherein the keyhole bore 101 is not adapted, because of the position of the slab 86, to receive the ordinary type of connector. The parts may be assembled and 60 interconnected by employing the connector 66 (Figure 4e) which fits into the bores 99 and 100, and by employing a pin 102, which fits into the bore 101, and by thereupon interconnecting the pin 102 and the projection 69 by means of the 65 female-type connector 44 (Figure 3a).

It will be obvious that the arrangement of parts, illustratively exemplified in Figures 7-12, and particularly in Figures 11 and 12, will in many cases present relatively difficult problems to the 70 young child, calling upon his or her ingenuity in bringing the parts into interconnected relation. Nevertheless, the structures are all fundamentally simple, and sufficiently so to hold the child's interest; and the process of assembly, 75

once the ingenuity of the child has been called into play, is fundamentally of the simplest type, involving nothing more than the interengagement of a pin with a hole.

5. For these reasons, the present toy is admirably adapted for use by the pre-school child, and has unusual attractiveness, fascination, and educational value.

As hereinbefore mentioned, it will be understood that changes in the details, herein described and illustrated for the purpose of explaining the nature of my invention, may be made by those skilled in the art without departing from the spirit and scope of the invention as expressed in the appended claims. It is, therefore, intended that these details be interpreted as illustrative, and not in a limiting sense.

Having thus described my invention, and illustrated its use, what I claim as new and desire to secure by Letters Patent is—

1. In a toy construction kit, a set of slabs, a set of connectors of dumb-bell shape, a set of pins having a uniform basic cross-section, and a second set of pins having a different uniform basic cross-section, the slabs having medial bores and also marginal keyhole bores, the connector heads and the bores conforming to said basic cross-sections, whereby the medial bores accommodate pins and the marginal bores accommodate either pins or connector heads to permit the assembly of selected elements into various toy structures.

2. In a toy construction kit, the combination with the elements of claim 1 of a set of auxiliary blocks having bores therein conforming to said basic cross-sections.

3. In a toy construction kit, the combination with the elements of claim 1 of at least one female type connector comprising a flat element with spaced bores therein, said bores conforming to said basic cross-sections and being adapted to engage over spaced pins, respectively.

4. In a toy construction kit, the combination with the elements of claim 1 of a set of wheels with central openings adapted to accommodate said pins.

5. As an element of a toy construction kit of the character described, a connector comprising a prismatic body of dumb-bell cross-section, the opposite heads being adapted to engage within marginal keyhole bores of elements to be inter-

connected, and a projection on the midportion of said body, said projection being parallel to the axes of said connector heads and conforming in cross-section to one of said connector heads.

6. As an element of a toy construction kit of the character described, a connector comprising a prismatic body of dumb-bell cross-section, the opposite heads being adapted to engage within marginal keyhole bores of elements to be interconnected, one connector head having an axial bore therethrough.

7. In a toy construction kit, a set of slabs, a set of connectors of slab thickness and dumb-bell shape, a set of pins of uniform cross-section, and a second set of pins of smaller uniform cross-section, the slabs having medial bores to receive pins and also marginal keyhole bores to receive pins or connector heads, some of the connector heads and some of the bores conforming in cross-section to the larger set of pins, the other connector heads and bores conforming in cross-section to the smaller set of pins.

8. In a toy construction kit, a set of slabs, a set of connectors of slab thickness and dumb-bell shape, a set of pins of uniform cross-section, and a second set of pins of smaller uniform cross-section, the slabs having medial bores to receive pins and also marginal keyhole bores to receive pins or connector heads, some of the connector heads and some of the bores conforming in cross-section to the larger set of pins, the other connector heads and bores conforming in cross-section to the smaller set of pins, at least one of the larger connector heads having an axial bore conforming in cross-section to the smaller set of pins.

9. As an element of a toy construction kit of the character described, a connector comprising a prismatic body of dumb-bell cross-section, the opposite heads being adapted to engage within marginal keyhole bores of elements to be interconnected, a marginally projecting shoulder on one end of one connector head, and a marginally projecting shoulder on the opposite end of the other connector head.

10. In a toy construction kit, the combination with the elements of claim 1, of at least one connector having one head conforming to one of said basic cross-sections while the other head conforms to the other of said basic cross-sections.

MAY J. ROBINS.

50
